Primary Examiner — Cynthia Underwood*(74) Attorney, Agent, or Firm* — McAndrews, Held & Malloy, Ltd.(57) **CLAIM**

The ornamental design for an hose guide, as shown and described.

DESCRIPTION

FIG. 1 is a perspective view of an hose guide.

FIG. 2 is another perspective view of the hose guide of FIG. 1.

FIG. 3 is a top plan view of the hose guide of FIG. 1.

FIG. 4 is a front elevational view of the hose guide of FIG. 1.

FIG. 5 is a left side elevational view of the hose guide of FIG. 1.

FIG. 6 is a rear elevational view of the hose guide of FIG. 1.

FIG. 7 is a right side elevational view of the hose guide of FIG. 1; and,

FIG. 8 is a bottom plan view of the hose guide of FIG. 1.

The broken lines represent portions of the structure that form no part of the claim; the wavy lines indicate indeterminate length.
